UNITED STATES PATENT OFFICE.

EDWARD A. CLOONAN, OF ST. LOUIS, MISSOURI.

SHEET-RETAINING ATTACHMENT FOR PRINTING-PRESSES.

1,302,310.

Specification of Letters Patent. Patented Apr. 29, 1919.

Application filed September 12, 1918. Serial No. 253,797.

To all whom it may concern:

Be it known that I, EDWARD A. CLOONAN, a citizen of the United States of America, a resident of the city of St. Louis, in the State 5 of Missouri, have invented certain new and useful Improvements in Sheet-Retaining Attachments for Printing-Presses, of which the following is a full, clear, and exact description, reference being had to the accompanying drawings, forming a part of this 10 specification.

This invention relates to improvements in sheet retaining attachments for printing presses, one of the objects being to provide 15 a very simple and inexpensive device of this kind which may be easily and quickly applied to a printing press so as to retain the paper on the platen. Another object is to produce a sheet retaining attachment consisting of a few simple elements easily adjustable relative to the platen so as to properly engage the paper.

With the foregoing and other objects in view, the invention comprises the novel construction, combination and arrangement of parts hereinafter more specifically described and illustrated in the accompanying drawings wherein is shown the preferred embodiment of the invention; however, it is 30 to be understood that the invention comprehends changes, variations and modifications which come within the scope of the claims hereunto appended.

Figure I is a fragmentary view of a portion 35 of a printing press equipped with a sheet retaining attachment embodying features of this invention.

Fig. II is an enlarged side elevation of the string gripping device.

Fig. III is an enlarged transverse section taken approximately on the line III— 40 III, Fig. I, showing the string gripping device.

Fig. IV is a detail view illustrating the slack adjuster to which one end of the string is secured.

To illustrate the manner of attaching the sheet retaining device to a printing press, I have shown a platen A provided with ears 50 B, an oscillatory bar C provided with pivot members D mounted in the ears B and a pair of gripper arms E adjustably mounted on the bar C. These elements may form part of an ordinary printing press, the gripper arms E being ordinarily used to secure 55 large sheets of paper to the platen A.

It will be observed that the arms E may be turned on the axis of pivot members D so as to move toward and away from the platen A. F designates a sheet of paper mounted 60 on the platen and positioned to be engaged by the printing type (not shown).

My improved attachment comprises a string 1 arranged over the platen and adapted to engage the sheet of paper F. If the 65 sheet of paper is provided with a margin line 2, or the like, the string 1 may be used as a guide, or gage, enabling the paper to be properly positioned on the platen. In this event, the sheet of paper provided with 70 the margin line 2, or the like, will be positioned with its margin line adjacent to and parallel with a portion of the string 1.

The attachment also includes a string gripper preferably consisting of a U-shaped 75 sheet metal clip 3 embracing one of the arms E and frictionally engaged with said arm so that it can be adjusted longitudinally thereof, a gripping jaw 4 preferably formed integral with said clip, and a gripping jaw 80 5 pivotally mounted at 6 so as to coöperate with the jaw 4. A spring 7 (Fig. II) may be used to force the gripping jaw 5 toward the jaw 4. Flanges 8, located at opposite sides of the gripping device, are perforated 85 to receive the string 1. The string is gripped by the jaws 4 and 5, and it is guided by the flanges 8.

9 designates a slack adjuster (Figs. I and IV) in the form of a U-shaped sheet metal 90 clip embracing one of the arms E. The slack adjuster is made of spring material and it frictionally engages the arm E. One end of the string 1 is secured to the slack adjuster 9, and the opposite end is fixed to an 95 anchor 10 adjustably mounted on one of the arms E. This anchor 10, like the elements 3 and 9, is a U-shaped sheet metal clip embracing the arm E on which it is mounted.

It will be apparent that the simple elements of my attachment can be easily and quickly applied to the arms E of a printing press, and that the clips 3 and 10 can be readily adjusted to any desired positions on the arms E so as to locate the string 1 in the 105 desired position relative to the platen. The arms E can be adjusted toward and away from each other, in a manner well understood in this art, and after all of the preliminary adjustments have been made, the 110 string is firmly pulled through the gripping device so as to tighten the clips 3 and 10 on

the arms E, at the same time tightening the string between the gripping device and the anchor 10. Thereafter, the slack adjuster 9 may be shifted on its arm E to tighten the string between the gripping device and the slack adjuster.

10 The tight portion of the string extending from the anchor 10 to the gripping device, overlies the sheet of paper F so as to retain the latter on the platen. The attachment is particularly intended to be used as a means for retaining small sheets of paper on the platen, preventing them from sticking to the type and compelling them to follow the 15 platen when the latter moves away from the type.

It will also be understood that the attachment may be used as an auxiliary means to coöperate with the ordinary means for securing the sheets of paper to a platen. However, I do not deem it necessary to show or 20 describe the ordinary means for securing the sheets.

I claim:

25 1. A printing press provided with a platen, arms movable toward and away from said platen, and a sheet retaining attachment comprising a flexible sheet retaining string extending approximately from one of said arms to the other, an anchor securing said string to one of said arms and a slack adjuster whereby the string is tightened and secured to the other arm.

30 2. A printing press provided with a platen, arms movable toward and away from said platen, and a sheet retaining attachment comprising a flexible sheet retaining string extending approximately from one of said arms to the other, an anchor securing said string to one of said arms, a slack adjuster whereby an end portion of said string is secured to the other arm, and a string gripper securing an intermediate portion of the string to the last mentioned 45 arm.

35 3. A printing press provided with a platen, arms movable toward and away from said platen, and a sheet retaining attachment comprising a flexible sheet retaining string extending approximately from one of said arms to the other, an anchor whereby said string is adjustably secured to one of said arms, and a string gripper adjustably securing the string to the other 50 arm.

40 4. A printing press provided with a platen, arms movable toward and away from said platen, and a sheet retaining attachment comprising a flexible sheet retaining string extending approximately from one of said arms to the other, and adjustable means whereby said string is secured to said arms, said adjustable means including a string-anchor mounted on and adjustable 45 longitudinally of one of said arms and a

slack adjuster for the string mounted on and adjustable longitudinally of the other arm.

45 5. A printing press provided with a platen, arms movable toward and away from the platen, and a sheet retaining attachment 50 comprising an anchor mounted on and adjustable longitudinally of one of said arms, a string gripper mounted on and adjustable longitudinally of the other arm, a slack-adjuster adjustably mounted on the last 55 mentioned arm, and a flexible sheet retaining string extending from said anchor, through said gripper and thence to said slack adjuster, the end portions of said string being secured to said anchor and slack 60 adjuster and an intermediate portion of the string being adjustably secured by said gripper.

6. A printing press provided with a platen, arms movable toward and away from the platen, and a sheet retaining attachment 65 comprising an anchor embracing and frictionally engaged with one of said arms, so that it can be readily adjusted longitudinally of the arm, a string gripper embracing and frictionally engaged with the other arm so that it can be readily adjusted longitudinally of the last mentioned arm, a slack adjuster embracing and frictionally engaged with the last mentioned arm so that it can be 70 readily adjusted longitudinally thereof, and a flexible sheet retaining string extending from said anchor, through said gripper and thence to said slack adjuster, the end portions of said string being secured to said anchor and slack adjuster and an intermediate portion of the string being adjustably secured by said gripper.

7. In a sheet retaining attachment for printing presses, a flexible sheet retaining 75 string, an anchor for securing one end portion of the string to the printing press, and a slack adjuster for securing the other end portion of the string to the printing press, said anchor and slack adjuster being in the 80 form of clips adapted to be adjustably secured to the printing press.

8. In a sheet retaining attachment for printing presses, a string anchor adapted to be adjustably secured to the printing press, 115 a string gripper also adapted to be adjustably secured to the printing press, and a flexible sheet retaining string secured to said anchor and adjustably held by said gripper.

9. In a sheet retaining attachment for 120 printing presses, a string anchor adapted to be adjustably secured to the printing press, a string gripper adapted to be adjustably secured to the printing press, a slack adjuster also adapted to be adjustably secured to the 125 printing press, and a flexible sheet retaining string passing through said gripper and having its ends secured to said anchor and slack adjuster.

10. In a sheet retaining attachment for a 130

printing press having a platen and a pair of arms movable toward and away from the platen, a string anchor adapted to be adjustably secured to one of said arms, a string gripper adapted to be adjustably secured to the other arm, and a flexible retaining string passing through said gripper and secured to said anchor.

11. In a sheet retaining attachment for printing presses, a string anchor adapted to be adjustably secured to the printing press, a string gripper also adapted to be adjustably secured to the printing press, said string gripper having a pair of gripping jaws and a string guide adjacent to said jaws, and a flexible sheet retaining string secured to said anchor, a portion of said string being arranged in said guide and secured by said gripping jaws.
12. In a sheet retaining attachment for a

printing press provided with a platen and a pair of arms movable toward and away from said platen, a string anchor comprising a U-shaped sheet metal clip adapted to be adjustably mounted on one of said arms, a U-²⁵ shaped sheet metal clip adapted to be adjustably mounted on the other arm, a pair of gripping jaws carried by the last mentioned clip, a slack adjuster comprising a U-shaped clip adapted to frictionally engage the last ³⁰ mentioned arm, and a sheet retaining string having its respective ends secured to said anchor and slack adjuster, an intermediate portion of said string being arranged between and adjustably secured by said gripping jaws.

In testimony that I claim the foregoing I hereunto affix my signature.

EDWARD A. CLOONAN.
